UNITED STATES PATENT OFFICE.

JACOB MOSES STEIN, OF WASHINGTON, DISTRICT OF COLUMBIA.

SHOULDER-PRESSING DEVICE FOR GARMENTS.

No. 922,733.

Specification of Letters Patent.

Patented May 25, 1909.

Application filed May 23, 1907. Serial No. 375,255.

To all whom it may concern:

Be it known that I, JACOB MOSES STEIN, a citizen of the United States, residing at Washington, District of Columbia, have invented certain new and useful Improvements 5 in Shoulder-Pressing Devices for Garments, of which the following is a specification.

This invention relates to a shoulder pressing device for garments.

In the pressing of garments, it has been difficult to press the shoulders of coats expeditiously and satisfactorily. The shoulders of coats are usually pressed upon the well-known "bosom" or "presser" blocks which 10 tend to defeat rather than accomplish the object in view. In the use of this old type of block, the shoulder of the garment is placed upon the narrower end of the pressing surface thereof. A damp cloth is then placed over 15 the shoulder and a hot iron passed over the damp cloth to steam the cloth of the garment so that the latter may be stretched. This stretching of the material of the garment is 20 usually accomplished by grasping the material upon opposite sides of the block and stretching the same by hand over the latter. The stretching is done alternately with the application 25 of the hot iron. The ordinary "bosom" or "presser" boards present a flat upper surface and when the steamed material of the 30 goods is stretched thereover it tends to flatten or broaden the shoulders from front to rear in direct contradistinction to a narrowing and raising of the shoulder. To effect a 35 proper or high shouldered garment it is essential that the shoulder be raised and narrowed from front to rear. An expert presser, regardless of the time he may consume, cannot possibly shape the opposite 40 shoulders alike with the use of the ordinary "bosom" or "presser" block, one side almost invariably being lower than the other, and surely so, when considerable time and 45 patience is not manifested in the work. The fact of the matter is that the workman is compelled to "guess" whether he has shaped 50 both shoulders alike. The workman is also hindered in his work in that he must continually shift the garment from one position to another upon the old type of block. In tailoring establishments time is obviously at 55 a premium and it is requisite to the best interests of the establishment that the garments be not only expeditiously but satisfactorily pressed to give the garment the proper shape or effect.

In the use of my improved shoulder presser form, both shoulders are raised to the same degree and shaped alike, without any particular attention being given the work, and 60 without shifting the garment from one position to another upon the form.

Another object of my invention is to provide a shoulder presser form embodying such characteristics that incident to the alternate 65 steaming and stretching of the goods, the material thereof at the shoulder will be lifted upwardly instead of flattened from front to rear to present high, square shoulders upon 70 each side of the garment.

Another object of the invention is to insure the proper shaping of each shoulder in the quickest possible time without the continual movement of the garment to different positions upon the presser form, the form in 75 the present instance itself providing the necessary shape and obviating the necessity of shifting the garment from one position to another during the pressing operation.

It is a still further object of my invention 80 to provide a pivoted presser block constructed and arranged for detachable engagement with the ordinary "bosom" or "presser" form or any other support.

It is still further designed to provide a 85 shoulder presser form embodying such characteristics that it may be rocked for the purpose of stretching the goods during the pressing operation, obviating the necessity of the expert presser using both hands to stretch 90 the material over opposite sides of the form as is necessary in the use of the old type of ironing block or board.

With the above and other objects in view, the present invention consists in the combination and arrangement of parts hereinafter more fully described, illustrated in the accompanying drawings and particularly pointed out in the appended claims, it being understood that changes may be made in the form, 95 proportion, size and minor details without departing from the spirit or sacrificing any of the advantages thereof.

In the drawings:—Figure 1 is a side elevation of my invention attached to an ordinary 100 "bosom" or "presser" block. Fig. 2 is a top plan view. Fig. 3 is a longitudinal sectional view. Fig. 4 is a transverse sectional view. Fig. 5 is a detail perspective view of the arm pit engaging member. Fig. 6 is a longitudinal sectional view of a second embodiment 105 of the invention. Fig. 7 is a transverse sec-

tional view of the second embodiment. Fig. 8 is an inverted plan view of the presser form of the second embodiment. Fig. 9 is a perspective view of another form of the invention. Fig. 10 is a view showing the shoulder pressing form in longitudinal section and the coöperating means for holding the garment illustrated in side elevation. Fig. 11 is a top plan view of the garment holding means shown in Figs. 9 and 10 detached from the ordinary "presser" form and the improved presser form. Fig. 12 is a side elevation of still another form of the invention.

Referring now to the accompanying drawings and particularly to Figs. 1 to 5 inclusive, the reference character 1 indicates an ordinary "bosom" or "presser" block to which my improved presser form is detachably secured by means of a suitable bracket 2 designed to embrace the narrower end 3 of the pressing surface of the old type of block 1.

The main features of the present invention reside in the presser form 4 and the arm pit engaging member 5, the presser block having its bottom inclined from an intermediate point toward one end and at such intermediate point being provided with a pair of spaced recesses 6 designed to receive the spaced perforated ears 7 formed at the top of the aforesaid bracket 2, which ears are designed to receive the pivot bolt 8 passed transversely through the form 4 whereby the latter may have pivotal movement for a purpose hereinafter explained.

To secure the bracket 2, and consequently the form 4, upon the ordinary "bosom" or "presser" board or other support against accidental displacement, I provide the bottom of the bracket 2 with a screw threaded perforation in which works a thumb screw 9 whose shank portion is designed to engage the under face of the part 3 of the ordinary presser board, as shown. This thumb screw 9 has the further function of securing the arm pit engaging member 5 firmly to the bracket 2, the arm pit engaging member 5 being curved and provided at its inner end with a comparatively elongated slot 10 designed to embrace the shank of the thumb screw 9, whereby the arm pit engaging member may be adjustably secured against the under face of the bracket 2 by means of the thumb nut 11. The arm pit member is curved and adjustable to accommodate different sized arm-holes.

The outer end of the arm pit engaging member 5 is broader than its inner end and flared upwardly upon opposite sides as indicated at 12 with its extreme outer end, including its flared portions 12, flared downwardly to form a lip 13.

One end of my improved presser form is shaped to fit the shoulder portion of the garment, as indicated at 14, and the other end 15 of the presser form is shaped to fit the col-

lar of the garment, the front, top and back of the form between the collar and shoulder portions 14 and 15, respectively, being concaved and merged into said end portions. The form decreases gradually in cross sectional diameter from the shoulder end to the collar end thereof to provide a pronounced shoulder end to the form. The inner end of the presser form is provided with a curved handle member 16 through the instrumentality of which the presser form may be rocked by hand or foot upon its pivot to stretch the material during the pressing operation. The presser form is preferably covered or padded by means of fabric or other suitable material 17 without altering the general shape of the form.

In the use of my present invention, the coat sleeve at the shoulder is placed upon the form 4 and the arm pit engaging member 5 adjusted to engage the inner end of the sleeve at the seam between the sleeve and shoulder of the garment. A damp cloth is then placed over the shoulder part of the garment and a hot iron applied to steam the material of the coat. The coat being steamed facilitates stretching thereof and this stretching of the goods is essential to the proper shaping of the shoulder. The pressing workman grasps the handle 16 with his left hand and in his right hand holds the iron. As he presses the garment with his right hand he presses down with his left hand upon the handle 16 gradually to raise the shoulder of the garment during the pressing operation, the arm pit engaging member coöperating in this stretching and raising of the shoulder. When it is desired to remove the garment from the presser form it is simply necessary to rock the form upon its pivot to bring the shoulder part of the form toward the arm pit engaging member, whereby the coat may be readily removed after it has been accurately and properly pressed into shape without the attending guess work manifested in the use of the old and well-known type of ironing block.

In Figs. 6 to 8, inclusive, I illustrate a modified form of invention, in which the general shape of form 4' is the same as that hereinbefore described, and in which the form is secured upon the ordinary "bosom" or "presser" forms in the same manner as heretofore explained. In this instance, however, the bracket, in addition to having the spaced perforated ears 7' and the transverse pivot bolt 8', has an upstanding segment 18 between the ears for disposition in the elongated recess 19 between the recesses 6', and which opens through the inner or collar end 15' of the form 4'. The said pivot bolt 8' passes through the segment plate 18 and the latter has its teeth 20 arranged for engagement by the inner end of the pivoted dog 21 which lies in the elongated recess 19 and ex-

130

tends slightly beyond the inner or collar end of the form 4' so that it may be moved upon its pivot pin 22 out of engagement with said teeth 20, the dog carrying a spring 23 for engagement with the curved plate 24 to hold the dog normally in engagement with the teeth of the segment plate 18. This modified form has an arm-pit engaging member 5' associated therewith, as in the first form described.

In the use of this second embodiment of the invention, the handle 16 of the first embodiment is obviated. The workman simply presses down upon the inner or collar end 15 of the form 4' gradually, or upon the curved plate 24, which may therefore serve as a handle, to cause a step by step lifting of the shoulder end of the form 4' to properly raise the shoulder of the garment. In the 20 first form this step by step movement is manifest but the workman has to keep his hand upon the handle 16, while in the second embodiment of the invention the dog 21 holds the presser form in its different 25 positions. This dog 21 prevents backward movement of the presser form until disengaged by the workman from the segment plate 18.

If desired, the aforesaid curved plate 24 30 may have an eye 25 in its outer end for the reception of the part 26 of the extension foot lever rod and which is clamped to the other part 27 of the latter by means of a clamp 28. The lower end of the part 27 of 35 the extension rod is secured in the eye 29 of the treadle 30. The rod is adjusted so as to hold the treadle upon a slight incline so that a slight pressure thereupon by the foot of the workman will obtain the step by step 40 pivotal movement of the form 4'. Thus the form 4' may be rocked by hand or foot or both as may be preferred.

In Figs. 9, 10 and 11 there is shown a third form of the invention in which the 45 shoulder presser form 4^a is the same as the form 4', including the form 4^a, spaced ears 6^a, segment plate 20' and dog 21'. However, the bracket 2^a has secured thereto at one end a curved arm 31 which is twisted at 50 32 to dispose its extremity 33 at an angle to its body portion. A pair of pincer arms 34 are pivoted together through a perforation in the extremity 33 by means of a pivot bolt 34'. The inner ends of the pincer arms 34 55 are adapted to grasp the arm pit of the coat near the seam between the shoulder and sleeve under the armhole upon the outside of the garment. To prevent slipping of the garment between the pincers when the form 60 4^a is moved upon its pivot, I lock the pincers by means of the spring controlled latch 35, the inner ends of the pincer arms carrying rubber or other sleeves to reduce friction.

In Fig. 12 I illustrate pincers 34^a shorter 65 than the pincers 34' and pivot the same

upon the upper end of the curved arm 31', the arm being clamped to the lower portion 36 of the ordinary "presser" or "bosom" board by means of the clamping plate 37 and thumb bolt 38. The pincers 34' hold 70 the coat while the form 4^b is rocked upon its pivot.

Either the arm pit engaging member or the pincers may be properly termed "means for holding the coat" during operation of 75 the pivoted presser form.

What is claimed is:—

1. In a shoulder pressing device, the combination with a pivoted presser form having its inner end terminating in a flaring portion 80 to provide a collar ironing surface and having its outer end terminating in a shoulder ironing surface, the portion of the form between the collar and shoulder ends having its top concaved to correspond with the depressions 85 in the garment between the collar and shoulder of the garment, and means constructed and arranged to engage the garment to effect a stretching of the latter between the form and said means when the form is moved in 90 one direction upon its pivot.

2. In a shoulder pressing device, the combination with a pivoted presser form having its inner end terminating in a flaring portion to provide a collar ironing surface and having 95 its outer end terminating in a shoulder ironing surface, the portion of the form between the collar and shoulder ends having its top concaved to correspond with the depressions 100 in the garment between the collar and shoulder of the garment, means constructed and arranged to engage the garment to effect a stretching of the latter between the form and said means when the form is moved in one direction upon its pivot, and means constructed and arranged to prevent accidental 105 backward movement of the form during the stretching operation.

3. In a shoulder pressing device, a form, means constructed and arranged to pivotally 110 mount the form to permit of an alternate raising and lowering of the ends thereof, and means constructed and confined within the form to prevent accidental backward movement of the latter during its pivotal movement in one direction.

4. The combination with a support; of a bracket secured to the support and provided with spaced upstanding ears; a presser form having spaced recesses in its bottom to receive said ears; a pivot pin passed transversely through the presser form whereby the latter is pivotally mounted upon the bracket; and an arm-pit engaging member arranged beneath said form and held in adjusted positions against the bracket.

5. The combination with a pivoted presser form having its inner end terminating in a flaring portion to provide a collar ironing surface and having its outer end terminating 130

in a flaring portion to provide a shoulder ironing surface the portion of the form between the collar and shoulder ends having its top concaved to correspond with the de-
5 pressions in the garment between the collar and shoulder of the garment, arm-pit engag-
ing means, and means whereby the form may be rocked upon its pivot to stretch the garment between said form and arm-pit engag-
10 ing means.

6. In a shoulder pressing device, the combination with a presser form, of means con-
structed and arranged to pivotally mount the form intermediate its ends to permit of an
15 alternate raising and lowering of the ends, an arm-pit engaging member arranged in spaced
relation to the form to effect a stretching of the garment between one end of the form and
said member when one end of the form is
20 raised, and a handle member carried by the form.

7. The combination with a support, of a bracket engaging the support; a presser form pivotally mounted upon the bracket;
25 an arm-pit engaging member arranged against the bracket, a member passed through the arm-pit engaging member and the bracket to secure the latter upon said support; means embracing the member
30 passed through the bracket to secure the arm-pit engaging member against displacement; and means whereby the presser form may be rocked upon its pivot to stretch the material between the form and the arm-pit
35 engaging member.

8. The combination with a presser form, of means constructed and arranged to pivotally mount the form intermediate its ends to permit of an alternate raising and lowering
40 of the ends, and an arm-pit engaging means coöperating with the form to effect a stretching of the garment when one end of the form is raised.

9. The combination with a presser form,
45 of means constructed and arranged to pivotally mount the form intermediate its ends to permit of an alternate raising and lowering of the ends, and an arm-pit engaging member adapted to engage the garment to effect a stretching of the latter between the form and said member when one end of the form is raised, said member being slidably and adjustably mounted.

10. In a shoulder pressing device, the
55 combination with a form having its inner end terminating in a flaring portion to pro-
vide a collar ironing surface and having its outer end terminating in a shoulder ironing surface, the portion of the form between the
60 collar and shoulder ends having its top concaved to correspond with the depression in the garment between the collar and shoulder of the garment, of means constructed and arranged to pivotally mount the form intermediate its ends to permit of an alternate

raising and lowering of the ends, an arm-pit engaging member to engage the garment to effect a stretching of the latter when the form is moved in one direction upon its pivot, and means for clamping the arm-pit 70 engaging member in adjusted position.

11. In a shoulder pressing device, the combination with a form having its inner end terminating in a flaring portion to provide a collar ironing surface and having its outer 75 end terminating in a shoulder ironing surface, the portion of the form between the collar and shoulder ends having its top concaved to correspond with the depression in the garment between the collar and shoulder 80 of the garment, of means constructed and arranged to pivotally mount the form intermediate its ends to permit of an alternate raising and lowering of the ends, an arm-pit engaging member to engage the garment to 85 effect a stretching of the latter when the form is moved in one direction upon its pivot, means for clamping the arm-pit engaging member in adjusted position, and means for preventing accidental backward 90 movement of the form during said stretching operation.

12. The combination with a pivoted presser form for garments having one end shaped to fit the shoulder portion thereof and the other end shaped to fit the collar portion of the garment, and a curved arm-pit engaging member coöperating with said pivoted form, the outer end of the arm-pit 95 engaging member being broadened and 100 curved upwardly at its sides with its ex-
tremity including the upwardly curved portions, formed to provide a semi-circular lip.

13. The combination with a support; of a bracket secured to the support and provided with spaced upstanding ears, and a toothed segment plate arranged between the ears; a presser form having spaced recesses in its bottom to receive said ears and said toothed segment plate, a pivot pin passed trans-
versely through the presser form and through the ears and segment plate, an arm pit en-
gaging member arranged beneath said form and held in adjusted positions against the bracket; and a spring actuated dog arranged 105 in one of the aforesaid recesses for engage-
ment with the teeth of the segment plate to prevent backward movement of the presser form when the latter is moved in one direction upon its pivot. 110

14. The combination with a support; of a presser form detachably mounted upon the support; an arm-pit engaging member ar-
ranged beneath the form; and a handle member carried by the presser form whereby 125 the latter may be rocked upon its pivot to stretch the garment between the form and the arm-pit engaging member.

15. The combination with a support; of a presser form detachably mounted upon the 130

support; an arm-pit engaging member arranged beneath the form; a handle member carried by the form; a treadle, and an adjustable connection between the treadle and 5 handle member.

16. The combination with a support, of a bracket secured to the support and provided with spaced upstanding ears and a toothed segment plate between the ears; a presser 10 form having spaced recesses in its bottom to receive said ears and toothed segment plate; a pivot pin passed transversely through the presser form whereby the latter is pivotally mounted upon the bracket; a curved handle 15 member carried by the presser form and bridging one of said recesses; and a pivoted spring actuated dog arranged within one of the recesses and normally in engagement with the teeth of the segment plate, the dog 20 projecting slightly beyond one end of the presser form.

17. The combination with a presser form, of means constructed and arranged to pivotally mount the form intermediate its ends 25 and permit of a step by step pivotal movement of the form, means coöperating with the form to engage the arm-pit of the garment to effect a stretching of the shoulder portion only of the garment when one end of 30 the form is raised upon its pivot, and means constructed and arranged to prevent accidental backward movement of the form during the stretching operation.

18. The combination with a support, of a 35 shoulder presser form pivotally mounted upon the support, and a curved slotted arm

pit engaging member arranged to engage the garment during pivotal movement of said form.

19. The combination with a bracket provided with spaced ears, of a presser form having spaced recesses to receive said ears, and a pivot pin passed through the presser form and said ears whereby the form may have pivotal movement upon the bracket. 40 45

20. The combination with an attaching means provided with spaced ears, of a presser form having spaced recesses to receive said ears, a pivot pin passed through the presser form and said ears, whereby the form may be 50 pivotally mounted upon said attaching means, and means coöperating with the form to effect a stretching of the garment between the form and last mentioned means when the form is moved in one direction upon its pivot. 55

21. In a coat shoulder pressing device, a pivoted form whose outer end is rounded on its upper surface and adapted for projection into the inner end of a coat sleeve with its other end disposed for engagement by the 60 collar of the garment, and means constructed and arranged to engage the arm-pit of the garment and hold the latter when the form is moved upon its pivot to effect a stretching of the garment between the shoulder and the 65 arm-pit of the garment.

In testimony whereof I affix my signature, in presence of two witnesses.

JACOB MOSES STEIN.
